UNITED STATES PATENT OFFICE.

FREDERICK N. GARDNER, OF BELOIT, WISCONSIN.

DRILLING-MACHINE.

SPECIFICATION forming part of Letters Patent No. 707,507, dated August 19, 1902.

Application filed November 8, 1901. Serial No. 81,566. (No model.)

To all whom it may concern:

Be it known that I, FREDERICK N. GARDNER, of Beloit, in the county of Rock and State of Wisconsin, have invented certain new and useful Improvements in Drilling-Machines; and I do hereby declare that the following is a full, clear, and exact description thereof, reference being had to the accompanying drawings, and to the letters of reference marked thereon, which form a part of this specification.

This invention relates to improvements in multiple drilling-machines of that class embracing a plurality of drill-spindles which are driven from a centrally-located shaft and a plurality of work-tables, one for each drill-spindle, which are movable toward and from the drills to feed the work thereto, said work-tables being so constructed that they are automatically advanced toward and retracted from the drills during the drilling operation.

The invention consists in the matters hereinafter set forth, and more particularly pointed out in the appended claims.

In the drawings, Figure 1 is a side elevation of a drilling-machine embodying my invention. Fig. 2 is a central vertical section thereof. Fig. 3 is a plan section on line 3 3 of Fig. 2. Figs. 4 and 5 are two views from opposite sides of the cam-ring on which are formed the cam-shoulder for advancing the work-tables to the drill. Fig. 6 is a fragmentary detail illustrating a section of the work-table support, showing one of the tables and its stem and showing also the table-actuating cam-ring and the connections between the same and said table-stem. Fig. 7 is a side view of the part shown in Fig. 6. Fig. 8 is a transverse section on line 8 8 of Fig. 6. Fig. 9 is a transverse section on line 9 9 of Fig. 6. Fig. 10 is a top plan view of the upper part of the machine. Fig. 11 is a horizontal transverse section on line 11 11 of Fig. 1.

As shown in the drawings, A designates a horizontal bed-plate or table, which is supported on vertical standards A' A', rising from a base-plate A^a, and A² designates a hollow column or pedestal rising upwardly from said table.

B designates a vertical shaft, which is contained within said hollow column and has bearing in short bearing sleeves or bushings

B' B' at the upper and lower ends of the columns. Said shaft projects at its lower end through and beneath the bed-plate A and is provided at its lower end with a horizontal beveled gear-wheel B², which meshes with a gear-pinion C, by which said gear-wheel and shaft B are rotated. Said pinion C is affixed to a horizontal shaft C', which is mounted at one end in one of the standards A' of the bed-plate and at its other end in an upright standard A³, rising from said plate. Said shaft is provided with a set of conical pulleys C², by which power is transmitted to drive the shaft B.

D designates a sleeve which surrounds or incloses the tubular column A² throughout the principal part of its length. Said sleeve rests on an annular horizontal bearing-shoulder a on the bed-plate A, said shoulder a receiving the vertical thrust of said sleeve and parts supported thereby. Said sleeve D supports near its upper end a drill-spindle support E and below said drill-spindle support a work-table support F. Said drill-spindle support E is non-rotatively fixed to the upper end of the sleeve D and rests on an upwardly-facing shoulder d on said sleeve. The work-table support is also affixed non-rotatively to said sleeve below said spindle-support and rests on a like exterior upwardly-facing shoulder d'. Said spindle-support is provided at its margin with a plurality of annularly-disposed vertical bearing-sleeves E', whose axes are parallel with the central axis of said support and concentric with the axis of the column A². Rotatively mounted in said bearings are vertical spindles E', having chucks e at their lower ends to receive the usual twist-drills e'. Affixed to the upper ends of said drill-spindles are a plurality of gear-pinions E², which are adapted to mesh with a central gear-wheel B³, non-rotatively affixed to the upper end of the shaft B above the upper end of the column A². Said gear-pinions are held in place on the spindles by means of nuts e², which have screw-threaded engagement with the upper ends of the spindles, and the gear-wheel B³ is similarly affixed to the shaft B by means of a nut b, which has screw-threaded engagement with the upper end of said shaft and engages the hub of said gear-wheel. A⁴ designates a bearing-

ring which surrounds the reduced part of the upper end of the column A² and is located between the gear-wheel B³ at one side thereof and the column A², sleeve D, and spindle-support E at the other side.

The work-table support is made generally similar to the spindle-support and is provided near its margin with a plurality of sleeves or tubular bearings F', whose axes are parallel to the central axis of said support. Said sleeves are located severally vertically beneath the spindles E⁴. Located within said bearings F' are stems G, which carry at their upper ends horizontal work-tables G', upon which the work is held while being drilled, said tables being circular and provided with undercut grooves to receive the usual jigs by which the work is fastened to the table. Said stems G are endwise movable but non-rotative in their bearings F', whereby the said tables may be moved toward and from the drills during the drilling operation. For this purpose the stems are herein shown as provided with longitudinal grooves g, Figs. 6 and 8, which are engaged by stationary keys or feathers F², attached to the table-support and projecting radially inwardly into the bearings toward said stems. Said keys, as herein shown, are located in vertical slots in the outer sides of the bearings F' and are held in place by means of screw-bolts f', passing transversely through said bearings at one side of the bore thereof and through the keys. The bolts f' being inserted through the parts of the bearings at opposite sides of the slot serve to tighten the sides of the slots against the keys, and thus firmly clamp the same in place. The keys, moreover, may be removed outwardly from the slots when the bolts are removed, so that the removal and insertion of the said keys are greatly facilitated. The work-table and spindle-supports by reason of the attachment thereof with the rotative bearing-sleeve B are maintained in the same relative positions, and said tables are automatically raised toward the drills during the drilling operation by the action of a cam. The specific mechanism for this purpose is made as follows:

H designates a stationary ring which surrounds the lower end of the sleeve D and is located beneath the work-table support F. Said ring is supported on standards H', which are affixed to the bed-plate A by screw-bolts h in the manner as shown in Figs. 2 and 3. Said ring is provided on its outer surface with a curved strip H², forming part of a cam-shoulder, which is adapted to be engaged by bearing-rollers g, projecting inwardly from collars G², which surround the lower ends of the work-table stems. Said curved strip H² consists of a continuous strip having at its entering end a short upwardly-inclined part h', which rises from a horizontal annular shoulder h² at the base of said ring H. Said short inclined portion h' of the cam-strip intersects the gradually-rising part h³

of said cam, which extends a suitable distance around the ring and rises gradually from one end thereof to the other. Said gradually-rising part h³ of the cam-strip intersects a short horizontal part h⁴, constituting the highest portion of the cam, which latter intersects a sharply-declining part h⁵, which joins with the lowest part of the cam, formed by the portion of the shoulder h² located between the ascending and descending portions of the cam-strip. h⁶ designates a short downwardly-inclined strip which is parallel with the part h⁵ of the cam-strip, between which strip h⁶ and the part h⁵ of the cam-strip is formed a groove which guides the bearing-rollers as they leave the highest part of the cam. The said sleeve D is given rotation, and the bearing-rollers of the work-table stems are carried over the cam-shoulder, formed, as described, to automatically advance and retract the tables by the following mechanism.

I designates a worm-gear ring which fits in an annular rabbet at the lower end of the sleeve, said ring being attached by screws or bolts i to an annular flange d³, formed above the rabbet in said sleeve D.

I' designates a worm-shaft mounted in bearings I² I² on the base-plate A, and the worm I³ of which engages the worm-gear I. Rotation of the sleeve D causes the spindle and work-table supports to revolve, and said revolution carries the lower ends of the stems of the work-tables around the cam-ring H, with the bearing-rollers of said stems traveling over the cam-shoulder thereof. Said tables are therefore gradually raised toward the spindles as the support rotates until the rollers come into contact with the horizontal bearing-surface of said cam, at which time the tables travel a short distance horizontally, their advance toward the drill-spindles being arrested. After passing said horizontal part of the cam the bearing-rollers come into contact with the descending part of the cam, which causes the work-tables to be retracted from the spindles.

In the use of the drilling-machine the work-table support and spindle-support are revolved at a comparatively slow speed, the actual speed depending upon the character of the work. The work is fastened to each table when the table is occupying its lowermost position or when the bearing-wheel thereof rests on the part of the cam-shoulder formed on the shoulder h² of the cam-ring, and as the tables gradually rise or are advanced toward the drilling-spindles the drilling of the work is effected. The work remains on the table until the table is again retracted, at which time the finished work is removed and a new piece of work fastened in place on the table.

The collars G² are capable of movement vertically on the work-table stems in order to adjust said tables to varying thicknesses of work. For this purpose said collars are split

and provided on the opposite sides of the split portions thereof with overlapping lugs g^2 , through which pass screw-threaded bolts which when tightened clamp the collars on the stems and when loosened permit said collars to slide on the stems. The collars G^2 are affixed non-rotatively on the work-table stems by means of short keys g^4 , which are set into grooves in the inner faces of the sleeves and project laterally into the grooves g of said stems. The keys are fastened to the collars G^2 by means of screw-bolts g^5 , which pass through the collars and into the keys in the manner shown in Fig. 6. Stops 15 are provided for limiting the vertical adjustment of the collars G^2 , which consist in this instance of two set-screws g^6 g^7 , which are seated in screw-threaded apertures in the bottom of the grooves of the stems above and below the collars G^2 and project outwardly into the paths of the keys of said sleeves. The purpose of said stops is, first, to prevent said collars being raised sufficiently in adjusting the same as to permit said collars to 25 strike the under side of the work-table support when the tables are in their uppermost positions in the operation of the machine, and, secondly, to prevent the tables being sufficiently depressed to permit said tables coming in contact with the upper surface of the work-table support when the tables are in their lowermost positions.

The structural details may be varied somewhat from that herein shown without departing from the spirit of the invention, and I do not wish to be limited to such details except as hereinafter made the subject of specific claims.

I claim as my invention—

- 40 1. The combination with a vertical column, of a revolving work-table support, annularly arranged, rotative drill-spindles which revolve with said work-table support, work-tables located severally beneath said drill-spindles and provided with stems which have sliding, non-rotative engagement with said work-table support, a concentric stationary cam-ring below said work-table support provided on its cylindric surface with an upwardly-facing cam-shoulder, laterally-directed bearing-rollers on the lower ends of said stems which have bearing on said cam-shoulder, and means for vertically adjusting said bearing-rollers on said stems.
- 45 2. The combination with a vertical column, of a revolving work-table support, annularly arranged, rotative drill-spindles which revolve with the work-table support, work-tables located severally beneath said drill-spindles and provided with stems which have sliding, non-rotative engagement with said work-

table support, a stationary concentric cam-ring below said work-table support and provided on its cylindric surface with an upwardly-facing cam-shoulder, laterally-directed bearing-rollers on the lower ends of said stems which have bearing on said cam-shoulder, means for vertically adjusting said bearing-rollers on said stems, and means on said stems for limiting the vertical adjustment of the bearing-rollers thereon.

3. The combination with a vertical column, of a revolving work-table support, annularly arranged, rotative drill-spindles revolving with said work-table support, work-tables located severally beneath said drill-spindles and provided with stems which have sliding, non-rotative engagement with said work-table support, a concentric, stationary cam-ring below said work-table support provided on its cylindric surface with an upwardly-facing cam-shoulder, collars surrounding the lower ends of said stems, laterally-directed bearing-rollers on said collars adapted for engagement with said cam-shoulder, 80 said collars being provided with inwardly-projecting parts adapted to enter longitudinal grooves in said stems, and being capable of longitudinal movement with respect to the stems to permit vertical adjustment of the 90 collars.

4. The combination with a vertical column, of a revolving work-table support, annularly arranged, rotative drill-spindles revolving with said work-table support, work-tables 95 located severally beneath said drill-spindles and provided with stems which have sliding, non-rotative engagement with said work-table support, a concentric, stationary cam-ring below said work-table support and provided on its cylindric surface with an upwardly-facing cam-shoulder, collars surrounding the lower ends of said stems, laterally-directed bearing-rollers on said collars adapted for engagement with said cam-shoulder, 100 said collars being provided with inwardly-projecting parts adapted to enter longitudinal grooves in said stems and being capable of longitudinal movement on the stems to permit vertical adjustment of the collars, and 105 stops in said grooves adapted for engagement with the projecting parts of the collars to limit the vertical adjustment of the collars on said stems.

In testimony that I claim the foregoing as 115 my invention I affix my signature, in presence of two witnesses, this 2d day of November, A. D. 1901.

FREDERICK N. GARDNER.
